UNITED STATES PATENT OFFICE.

JOHN J. SULLIVAN, OF CARBONDALE, PENNSYLVANIA.

SPARK-ARRESTER.

SPECIFICATION forming part of Letters Patent No. 780,454, dated January 17, 1905.

Application filed May 24, 1904. Serial No. 209,504.

To all whom it may concern:

Be it known that I, JOHN J. SULLIVAN, a citizen of the United States, residing at Carbondale, in the county of Lackawanna and State of Pennsylvania, have invented new and useful Improvements in Spark-Arresters, of which the following is a specification.

This invention relates to spark-arresters adapted for use in connection with the stacks 10 of locomotive-engines; and the primary object of the same is to provide simple and effective devices within the locomotive smoke-box to deflect the products of combustion, such as cinders and heated particles, and prevent escape thereof from the stack by causing them to be discharged or deposited into a receptacle or receiving means provided therefor in the locomotive structure.

The invention consists in the construction 20 and arrangement of the several parts, which will be more fully hereinafter set forth.

In the drawings, Figure 1 is a transverse vertical section through the front end of a locomotive smoke-box and a portion of the stack 25 therefor, showing the improved spark-arrester applied thereto. Fig. 2 is an elevation of the body of the spark-arrester. Figs. 3 and 4 are plan views, respectively, of upper and lower reticulated closures for the body. Fig. 5 is 30 a view similar to Fig. 1, showing a modification in the construction. Fig. 6 is an elevation of the lower extremity of the stack extension and reticulated attachment therefor.

Similar numerals of reference are employed 35 to indicate corresponding parts in the several views.

Referring to Figs. 1, 2, 3, and 4, the numeral 1 designates a locomotive smoke-box, and 2 the usual stack. The upper end of a 40 stack extension-pipe 3 is fitted in and secured to the lower end of the stack 2, the pipe 3 projecting far enough downwardly into the smoke-box 1 ahead of the usual flues in the latter to coöperate with an exhaust-pipe 4, having an upwardly-projecting tip 5. The 45 spark-arrester has an hour-glass-shaped body 6, held in place by arms 7, secured to the upper portion thereof and to the extension 3 adjacent the point of jointure of the latter to the 50 lower end of the stack, the said arms having

angular terminals 8, bearing against the extension and secured thereto by bolts 9. The upper portions of the arms 7 are curved and closely bear against the inner surface of the smoke-box. To facilitate the securement of 55 the lower terminals of the arms to the upper part of the body 6 of the arrester, angular blocks 10 are used and present outer vertically-straight surfaces against which the said lower ends of the arms are applied. The lower 60 extremity of the extension 3 projects below the waist or intermediately-constructed portion 11 of the body 6, and over the upper and lower open ends of said body reticulated screens or covers 12 and 13 are respectively 65 secured, the extension 3 projecting through the center of the upper screen or cover 13 and the tip 5 of the exhaust-pipe 4 extending upwardly through the center of the lower screen or cover 12.

The modification shown by Figs. 5 and 6 embodies the same stack extension 3, stack 2, exhaust-pipe 4, having a tip 5, and arms 7, arranged in the boiler 1, as hereinbefore set forth. The body 6 of the arrester is also similar to that shown by Figs. 1 and 2; but the upper and lower ends of said body in this instance are fully open, and over the lower end of the extension 3 within the lower part of the body a downwardly-flaring screen or guard 14 75 is applied and has a closed reticulated bottom 15, through the center of which the tip 5 upwardly projects similar to the arrangement shown by Fig. 1, with the exception that the said tip passes through the screen 12, attached 80 to the bottom of the body.

The operation in both forms of the device shown is precisely the same, and both screens 12 and 13 and the screen 14 prevent the passage of cinders or products of combustion from 90 the smoke-box into and upwardly through the extension 3 and stack 2 without interfering in the least with the draft or obstructing the latter in its direct application to the stack by surrounding the extension 3 with a partial closure 95 similar to the body 6 and providing the latter with inclined surfaces. The cinders or products of combustion are drawn toward the arrester attachment and after obstruction in escape of the same through the extension and 100

stack by the means set forth the cinders or products of combustion fall into a lower receptacle usually provided for this purpose. In the form of the device set forth the cinders and products of combustion will strike against the screens 12 and 13, the smoke being allowed to escape. In the form shown by Fig. 5 the smoke and products of combustion are drawn into the body 6, the smoke passing out through the extension 3 and stack 2, and the cinders and other coarse products falling from the body.

The improved spark-arrester may be easily applied in operative position, and to meet various applications changes in the proportions and dimensions may be resorted to without departing from the spirit of the invention.

Having thus fully described the invention, what is claimed as new is--

- 20 1. The combination with a smoke-box having a stack, of a stack extension projecting downwardly into the smoke-box, a substantially hour-glass-shaped spark-arrester arranged around the lower portion of the extension and suspended from the latter, a screen means coöperating with the extension, and an exhaust-pipe extending upwardly through a part of the screen means, said exhaust-pipe and extension being separated from each other.
- 25 2. The combination with a smoke-box and stack of a locomotive, of an extension secured

to the lower end of the stack and projecting downwardly into the smoke-box, a spark-arrester body of hour-glass-shaped form arranged around the lower extremity of the extension, a screen means coöperating with the said body and extension, and an exhaust-pipe having its upper terminal projecting through a portion of the said screen means, said exhaust-pipe and extension being separated from each other.

3. The combination with a smoke-box and stack of a locomotive, of an extension secured to the lower end of the stack and projecting downwardly into the smoke-box, a spark-arrester body arranged around the lower extremity of the extension and having the upper and lower extremities outwardly flaring, perforate coverings over the upper and lower ends of the body, the extension passing through the center of the upper covering, and an exhaust-pipe having the upper extremity thereof passing through the center of the lower covering and located adjacent to the lower end of the extension.

In testimony whereof I affix my signature in presence of two witnesses.

JOHN J. SULLIVAN.
